TOOL TO PRESET CONTACT STABS ON CONNECTION BLOCKS

Bernhard H. Schwarz, Monvale, N.J., assignor to Consolidated Edison Company of New York, Inc., New York, N.Y., a corporation of New York

Filed July 27, 1965, Ser. No. 475,168
10 Claims. (Cl. 72—479)

ABSTRACT OF THE DISCLOSURE

Hand tool having elongated shank with fluted tip at lower end for forcing into stab slots to spread same; guide sleeve slidably mounted on shank to align shank with stab.

This invention relates to a method and apparatus for presetting contact stabs mounted on electrical contacts and more particularly in one form thereof to a tool for realigning slots in male contact stabs on electrical connection blocks. Among many possible uses, this invention is particularly adapted for use in connection with a removable interrupting element for use with withdrawable air-blast circuit breakers to provide reliable control and protection of power systems. In this type of installation one connection block is provided with a plurality of spaced male contact stabs and a second mating connection block is provided with a like plurality of female contact members.

Heretofore, considerable difficulty has been experienced with contact stabs on connection blocks due to the fact that after the contact stab has been pressed into engagement with the corresponding female contact member one or more times, there is a tendency for the female contact member to permanently deflect or compress the stab member. While resiliency exists in the stab member tending to return the prongs to their original positions, a certain permanent deflection occurs. As a result of this deflection, the stab members do not properly engage their corresponding female contact members, thereby causing unreliable and poor connections. A plurality of stabs and a corresponding plurality of female members tends to accentuate the problem.

Heretofore attempts have been made to rectify this difficulty, but they have not been entirely successful. Operators have inserted screwdrivers into the slots in the male stab in an attempt to preset the spacing, but this is haphazard, inaccurate and unreliable.

Briefly, this invention contemplates the provision of a tool for presetting stabs mounted on connection blocks comprising an elongated shank which has a fluted portion at the lower end thereof and a collar disposed adjacent the flutes. The flutes are formed by a plurality of raised faces, and a lower tip is formed by an upwardly increasing taper at the lower end of the shank. Also, the raised faces have upwardly increasing widths for engaging the slots in said stabs. A handle may be connected to the upper end of the shank for manipulating the tool. An elongated guide sleeve encompassing the lower end of the shank is provided having one portion thereof disposed closely adjacent the shank and another portion thereof engaging said connection block for aligning the shank with respect to the stab to be preset. The collar is engageable with the end of the stab to limit the downward travel of the shank during operation of the device.

The invention in another form thereof comprises a method of presetting contact stabs by inserting a guide sleeve into the recess surrounding the contact stab in a connection block, and lowering a fluted shank into said sleeve until the tip engages the end of the stab. Thereafter, the method comprises twisting the shank a partial

2

revolution until it registers with the slots, and thence, downwardly pressing the shank into the slots until a collar mounted on the shank engages the end of the stab, and finally withdrawing the shank and sleeve from the so preset stab.

An important feature of the invention is the provision of a new and improved tool to preset the slots in contact stabs mounted on connection blocks which overcomes the aforementioned difficulties.

Another feature of this invention resides in the provision of a tool to preset contact stabs which is of simple well-balanced construction, which is readily and economically fabricated and assembled on a mass production basis, and which is sturdy and durable, being capable of a long service life of severe usage.

A further feature of the invention resides in the provision of a new and improved tool for realigning the slots in electrical male plugs which operates easily, accurately and reliably.

These and other objects, features and advantages of the invention will become more fully apparent from the following detailed description of the invention when taken together with the accompanying drawings in which:

FIGURE 1 is a perspective view showing a mating pair of connection blocks one of which has a plurality of male contact stabs mounted thereon and the other has a corresponding plurality of female connecting members mounted thereon;

FIGURE 2 is a vertical sectional view through the center of a contact stab and a female contact member in engagement one with the other;

FIGURE 3 is a plan view showing a plurality of contact stabs mounted on a connection block;

FIGURE 4 is a vertical sectional view taken along the line 4—4 of FIGURE 3 and showing a tool, constructed in accordance with the invention, positioned in engagement with the upper end of a stab;

FIGURE 5 is a fragmentary vertical sectional view showing a tool, according to the invention, in operative position for realigning the slots in an electrical male plug or stab;

FIGURE 6 is a fragmentary perspective view showing the fluted tip of the shank of the tool and including the collar; and

FIGURE 7 is an end view of the shank of the tool showing the tip thereof.

Referring in particular to FIGURE 1, there is shown a male connection block 10 and a corresponding female connection block 12, the male connection block having a plurality of contact stabs or male plugs 14 and the female connection block 12 having a plurality of female contact members 16. The connection block 10 is mounted on a circuit breaker 17, FIGURES 3 and 4, by means of lugs 18 having bolt holes 20 for bolts 21.

As best seen in FIGURE 2, the female contact member 16 is mounted in a hexagonal recess 22 in the connection block 12, said recess being interrupted by a shoulder portion 24. The female member 16 is secured in position by means of a locking member 26 which has a shoulder portion 28 engageable with the shoulder 24 of the connection block 12. The locking member 26 has a longitudinally extending threaded portion 30 which fits into the threaded portion 32 of the female member 16. When assembled the locking member 26 threadably engages the female member 16 to clamp the shoulder 24 of the contact 12 between shoulders 28 and 34.

Still referring to FIGURE 2, the female contact member 16 is provided with a recess 36 for receiving the stab or male contact member 14, as shown. The stab or male contact member 14 is mounted in a hexagonal recess 37 and is secured to the connection block 10 by locking member 38 which is identical to locking member 26.

Accordingly, locking member 38 has a threaded portion 40 which engages the threaded portion 42 of the stab 14 so that shoulder 44 and shoulder 46 of the male contact member engage shoulder 48 of the connection block 10.

As best seen in FIGURE 3, each of the stabs or male contact members 14 is provided with a plurality of longitudinally extending slits or slots 50, two being shown in the form of a cross.

Usually the stab member is fabricated from resilient material, and hence, tends to return to its original configuration subsequent to removal thereof from the female member. However, after one or more contacts have been made the stab tends to take a permanent "set" in a deformed configuration, thereby closing or partially closing the slot 50. A slot is shown at 52, FIGURE 3, in its original configuration and is shown at 54 in its closed or deformed configuration.

According to the invention, a tool 56 for presetting the slots in the contact stabs 14 comprises a shank 58, FIGURES 4 and 5, having a handle 60 connected to the upper end thereof as at 62 for manipulating the tool. The lower portion of the shank 58 is provided with a plurality of raised faces 64, FIGURES 4-7, forming flutes 66 therebetween, and includes a lower tip 68 formed by an upwardly increasing taper. Further, the raised faces 64 have upwardly increasing widths for a purpose which will be discussed more fully hereinafter.

As best seen in FIGURE 6, the shank 58 is provided with a collar 70 disposed adjacent the fluted portion. This collar serves to limit the downward travel of the shank 58 during operation of the tool as shown in FIGURE 5.

Referring to FIGURES 4 and 5, an elongated bushing or guide sleeve 72 encompasses the lower end of the shank 58. This sleeve includes an upper portion 74 and a lower portion 76 which are interconnected as by means of a press fit shown at 78. The upper portion 74 has a reduced inside diameter which loosely engages the shank 58, as at 79, thereby aligning the guide sleeve 72 with respect to the shank 58. The lower portion 76 of the sleeve 72 is provided with a lower projection 80 of reduced outside diameter which slidably fits into the recess 37 encompassing the stab 14, as shown in FIGURES 4 and 5, to align the sleeve 72 with respect to the connection block 10, thereby aligning the shank 58 with respect to the stab 14. It is noted that after assembly the freely slideable shank 58 is confined within the sleeve 72 by the upper shoulder 82 and the lower shoulder 84 of the sleeve 72 between which the shank is free to move until its collar 70 abuts either of the same.

In operation, when the slits or slots become pinched through use as indicated at 54, FIGURE 3, the tool 56 is brought into position. The sleeve 72 is placed over the stab 14 as shown in FIGURE 4 so that the lower projection 80 thereof extends into the recess 37 of the connection block 10, as shown. The shank 58 is thence lowered until the tip 68 engages the end of the stab 14, as shown in FIGURE 4. Thereafter, the shank 58 is rotated a partial revolution by means of handle 60, until the raised surfaces 64 register with the slots 54. Then the shank 58 is pressed downwardly into the slots until the collar 70 engages the end of the stab 14 as shown in FIGURE 5. It will be appreciated that the raised faces 64 have upwardly increasing widths so that the depth to which the shank is pressed determines the width of the slot in the stab 14. Accordingly, the upper end width of the raised faces 64 determines the width to which the slots will be widened, and the collar 70 accurately determines when full insertion of the faces 64 has been made. Actually, due to the resiliency of the material, it is preferable to open the slots to a width slightly in excess of the final desired width in order to allow the material to resiliently return a short distance after removal of the tool, and for this reason the width of the taper at the upper end of the faces 64 is made slightly oversized with respect to the

desired, normal spacing of the slots 50. Thereafter, the tool 56 is withdrawn from the stab 14 by means of upward movement of the handle 60 so as to lift the shank 58 until the collar 70 engages the shoulder 82 of the sleeve. The tool is then withdrawn entirely from its operative position.

Thus has been described a tool for presetting contact stabs on connection blocks which achieves all of the objects of the invention.

What is claimed is:

1. A tool to preset a contact stab mounted on a connection block, said stab having a plurality of open slots, said tool comprising an elongated shank, a fluted tip at the lower end of said shank presenting a plurality of flutes corresponding in number and arrangement to said plurality of stab slots for respectively engaging the same, and an elongated guide sleeve mounted for axial slideable movement on said shank adjacent its said lower end, said sleeve having a portion for engaging said connection block to position said shank in alignment with said stab, whereby said flutes are guided in their said engagement with said stab slots.

2. A tool to preset a male contact stab mounted on a connection block, said stab having a plurality of longitudinally arranged, open ended slots, said tool comprising an elongated guide sleeve, an elongated shank longitudinally slideable within said guide sleeve, a fluted tip at the lower end of said shank, a portion of said sleeve disposed closely adjacent said shank for aligning said sleeve with respect to said shank, the lower portion of said sleeve being engageable with said connection block for aligning said shank with respect to said male contact stab to be preset.

3. A tool for presetting longitudinally arranged open ended slots in an electrical male contact stab mounted on a connection block, said tool comprising an elongated guide sleeve, an elongated shank longitudinally slideable within said guide sleeve, a fluted tip at the lower end of said shank, a collar disposed adjacent said flutes, a portion of said sleeve above said collar being disposed closely adjacent said shank for aligning said sleeve with respect to said shank, the lower portion of said sleeve being engageable with said connection block for aligning said shank with respect to said male stab to be preset, and handle means for said tool.

4. A tool for presetting longitudinally arranged, open ended slots in an electrical male stab mounted in a recess on a connection block, said tool comprising an elongated guide sleeve, an elongated shank, longitudinally slideable within said guide sleeve, a fluted tip at the lower end of said shank, a collar disposed adjacent said flutes, a handle connected to the upper end of said shank for manipulating said tool, a portion of said sleeve above said collar being disposed closely adjacent said shank for aligning said sleeve with respect to said shank, the lower portion of said sleeve extending below the fluted tip of said shank and being longitudinally slideable within the recess in said connection block for aligning said shank with respect to said male stab to be preset, and said collar being engageable with the end of said male stab to limit the downward travel of said shank during operation of said tool.

5. A tool to preset longitudinally arranged and open ended slots in a contact stab mounted on a recessed shoulder on a connection block, said tool comprising an elongated guide sleeve having a lower projection, an elongated shank longitudinally slideable within said guide sleeve, a handle connected to the upper portion of said shank, a fluted portion at the lower end of said shank, the number of flutes corresponding to the number of slots in each contact stab, said fluted portion having a lower tip and an upwardly increasing taper, a portion of said sleeve engaging said shank, and said lower projection engaging said recessed shoulder on said connection block for aligning said shank with respect to said stab.

6. A tool to preset open slots in a stab mounted on a

connection block, comprising an elongated shank, a plurality of raised faces forming flutes at a lower end of said shank for respectively engaging said stab slots, each of said raised faces having increasing width in upward direction relative to said shank, and said lower end of the shank including a lower tip having upwardly increasing taper and a guide sleeve slidably mounted on said shank and having means for engaging said connection block, whereby said flutes are guided in their said engagement with said stab slots.

7. A tool to preset slots in a stab mounted on a connection block according to claim 6 wherein a collar is disposed adjacent said flutes on said elongated shank, said collar being engageable with the end of a contact stab to limit the downward travel of said shank during operation of said tool.

8. A tool to preset slots in a stab mounted on a connection block according to claim 6 wherein the upwardly increasing widths of said raised faces are wider than the respective desired opening of the respective slots.

9. A tool to preset longitudinally arranged, open ended slots in a contact stab mounted on a recessed shoulder on a connection block comprising an elongated guide sleeve, an elongated shank longitudinally slideable within said guide sleeve, a handle connected to the upper portion of said shank, a plurality of raised faces forming flutes at the lower end of said shank, each of said faces corresponding to a slot in said contact stab, said lower end of said shank having a lower tip formed by an upwardly increasing taper, the raised faces having upwardly increasing widths, a collar disposed adjacent said flutes, a

portion of said sleeve above said collar being disposed closely adjacent said shank for aligning said sleeve with respect to said shank, the lower portion of said sleeve extending below the fluted tip of said shank and engaging the recessed shoulder on said connection block adjacent the contact stab for aligning said sleeve with respect to said shank and with respect to said contact stab to be preset, said collar being engageable with the end of said contact stab to limit the downward travel of said shank during operation of said tool.

10 10. A tool for presetting a contact stab mounted on a connection block, said stab having a plurality of slots, said tool comprising an elongated guide sleeve having an upper shoulder and a lower shoulder, an elongated shank freely, longitudinally slideable within said guide sleeve, a fluted tip at the lower end of said shank, a collar carried by said shank, said shank being confined within said sleeve by said collar engaging said upper shoulder in one direction and by said collar engaging said lower shoulder in the other direction, whereby said fluted tip remains protectively disposed within said sleeve in all positions of said shank with respect to said sleeve.
